UNITED STATES PATENT OFFICE.

FRED W. McCORMICK, OF GRAND RAPIDS, MICHIGAN.

DESIGN FOR A CUPBOARD LATCH.

Application filed November 22, 1927. Serial No. 24,243. Term of patent 14 years.

To all whom it may concern:

Be it known that I, FRED W. McCORMICK, a citizen of the United States, residing at the city of Grand Rapids, in the county of Kent and State of Michigan, have invented a new, original, and ornamental Design for Cupboard Latch, of which the following is a specification, reference being had to the accompanying drawing, forming a part thereof.

The figure is a perspective view of a cupboard latch showing my new design.

I claim:

The ornamental design for a cupboard latch, as shown.

FRED W. McCORMICK.
